ALBERT H. MORTON, OF LOWELL, MASSACHUSETTS.

ROVING-CREEL FOR SPINNING-FRAMES AND THE LIKE.

1,144,720.

Specification of Letters Patent. Patented June 29, 1915.

Application filed September 12, 1912. Serial No. 719,963.

To all whom it may concern:

Be it known that I, ALBERT H. MORTON, a citizen of the United States, residing at Lowell, in the county of Middlesex and State 5 of Massachusetts, have invented certain new and useful Improvements in Roving-Creels for Spinning-Frames and the like; and I do hereby declare the following to be a full, clear, and exact description of the invention, 10 such as will enable others skilled in the art to which it appertains to make and use the same.

The present invention relates to an improvement in roving creels for spinning frames and the like.

Roving bobbins supplying roving to spinning frames are supported in a creel mounted on the frame. In cases where double roving is used, a so-called "two-story" creel is 20 used wherein the bobbins are mounted on skewers supported in vertical position revolving in porcelain steps so that practically the only resistance offered to the rotation of the bobbin is that between the foot of the 25 skewer and the porcelain step. The limited space in which the bobbins are supported requires the use of two bobbins, one behind the other, on each side of the frame, and inasmuch as the usual size of a bobbin for a 30 frame in which the spindles are spaced $2\frac{1}{4}$ inches apart is $3\frac{1}{2}$ or 4 inches in diameter, it is apparent that the full bobbins have only $\frac{1}{4}$ inch clearance. In replenishing the roving supply the skewers have to be removed from 35 their bearings to remove an empty bobbin and to replace it with a full one, and upon the exhaustion of one of the rear bobbins, the operative is required to take out the front bobbin as well as the empty bobbin, and 40 then, after putting the former front bobbin in the place of the empty bobbin, to put another full bobbin in the front position and piece the roving. The inaccessibility of the rear bobbin without first removing the front 45 bobbin is one of the things which renders tending this form of creel laborious for the operative. Besides, it is apparent that where the bobbins are placed so close together as is required in this creel, the rear bobbins

are not easily observable, particularly as it is 50 the usual practice to put the full bobbin in the front position. Furthermore, in cleaning the top of the frame between the roller beams, considerable care is required to be 55 exercised, as but a slight contact with the roving or a bobbin is sufficient to break the roving.

The object of the present invention is to reorganize and improve the construction of the roving creels for spinning frames in order 60 to secure accessibility of the bobbin for convenient replenishment, facility of observation of the bobbins, durability of construction, facility and cheapness of manufacture, and economy of labor on the part of the operative in cleaning and tending the machine.

Bearing in mind that roving has a very low twist-constant, it is apparent that it can be utilized to rotate the bobbins only when a very small tension is exerted thereon, because the roving has a very slight tensile strength and is easily stretched or broken. So, in the creel forming the subject of this invention, the bobbin is so mounted as to be capable of turning by the exertion of a strain 75 thereon within the tensile strength of roving and without stretching or breaking it, and the creel pins for supporting the bobbins are arranged in such a way as to conduce to their easy removal and replacement for the 80 purpose of replenishing the roving supply, so that they are conveniently observable by the operative, and so that they shall be capable of being rotated by strains exerted thereon within the extremely slight strength of 85 the roving. To these ends the rotary creel pins for carrying the bobbins are mounted upon bearings of sufficiently low friction to permit the rotation of the bobbin without the exertion on the roving of a stretching or 90 breaking strain. Furthermore, the creel pins are so located that all of the bobbins are accessible for the removal of empties and the putting on of full bobbins without requiring the disturbance of more than the particular 95 bobbin necessary to be replaced. This is accomplished in the illustrated embodiment by arranging them in inclined position one

above the other on a creel frame, so that all of the creel pins are freely accessible. This arrangement conduces not only to reducing the labor of the operative, but to facility of 5 cleaning the frame, as the top of the frame is freely accessible without interference with or liability of striking the bobbins.

In the accompanying drawings illustrating the preferred form of the invention, 10 Figure 1 is a transverse sectional elevation of the creel, and Fig. 2 is an enlarged longitudinal sectional elevation of one of the rotary creel pins.

The supports 1 of the frame of the machine carry the roller beams 2 upon which the roll stands 3 are mounted, supporting the drawing rolls 4 which pull the roving from the bobbins, draw it and deliver it to the spindles. The sheet metal cover 5 extends from roller beam to roller beam, its edges are turned down, as shown, and rest upon the upper surfaces of the supports. The creel posts 6 are supported in the supports 1, being secured therein by set screws 20 7, and passing through holes in the cover 5. The creel posts carry a series of rail brackets 8 secured to the posts by set screws 9. To the upper ends of the creel posts are secured the pan brackets 10 by means of set screws 25 11. On the pan brackets is secured the pan 12 for holding a supply of roving and receiving empty bobbins. The rail brackets have inclined surfaces adapted to receive the rails 13, the brackets being provided with 30 lips to engage the edges of the rails so as to afford adequate support therefor. The rails 13 consist of bars of iron secured to the rail brackets and extending longitudinally of the machine, inclined as shown, to hold the 35 creel pins projecting outwardly in opposite directions at right angles to the rails. The creel pins 14 for the bobbins are revolvably mounted on the rails 13. Each pin is mounted on a stud 15 having a reduced 40 threaded end which is received in a hole in the creel rail and secured by means of a nut. The creel pin consists of a bottom sleeve 16, a tube 17 and a cap 18, and is supported on two ball bearings 19 and 20. The bottom 45 sleeve 16 is provided with an outwardly projecting shoulder forming a bobbin rest, and with a ball race for the lower ball bearing 19. The other member of the bearing 19 is formed by cutting a groove in the stud 15. The cap 18 is provided with a ball race for 50 the upper bearing 20, the other member of which is formed upon the end of the stud 15.

The creel pin is assembled on the stud 15 by pressing the tube 17 upon the bottom 55 sleeve 16, inserting the balls of the bearing 19 and supporting the parts in proper position with relation to each other, and then forcing the cap 18 into the end of the tube 17, the balls of the bearing 20 being placed

in position before the parts are forced together. The cap 18 is provided with a shoulder which engages the end of the tube 17, the portion above the tube being of the same size as the outside of the tube. Beyond this, the end of the cap is made frusto-conical 70 to facilitate placing the bobbins on the creel pin. The creel pin, as seen in Fig. 1, is made sufficiently long to extend into the bobbin beyond its center of gravity. Two rovings (from two bobbins) are, as illustrated, 75 led to each roving trumpet or guide 21 which directs the rovings to the drawing rolls.

The lowermost bobbin is located a little distance above the top of the frame so as to afford room for swinging up the cap bar 80 containing the top rolls, and therefore the top of the frame is easily accessible for cleaning. Each of the bobbins of this creel is directly accessible to the operative without interference with any other bobbin, so 85 when a bobbin is exhausted the operative can remove the empty bobbin with one hand, replace it with a full bobbin with the other hand, and immediately piece the roving. This reduces the amount of labor imposed 90 upon the operative in replenishing the roving, not only by reason of the elimination of the removal of the front bobbins to get at the rear ones, but by reason of the fact that there is no skewer to be removed with and 95 replaced with the bobbin. Again, every bobbin is in plain, full sight of the operative, and may be continuously and easily observed.

The construction is simple and therefore 100 cheap. It is also strong, and therefore durable.

It is essential, it will be observed, that the bobbins be capable of being rotated by the exertion thereon of a very slight strain 105 within the stretching and breaking strength of the roving to which such strain is transmitted, so it is necessary that the creel pins have low-friction bearings, and while ball bearings are preferred because of the small 110 amount of friction which they develop, other forms of low-friction bearings may be used, and are within the purview of the invention.

The invention, viewed in its broader aspects, contemplates any form of roving creel 115 for spinning frames and the like wherein the creel pins are accessible, visible, and mounted in inclined position upon low-friction bearings.

Having thus described the invention, what 120 is claimed is:—

A spinning frame or the like having, in combination, drawing rolls mounted upon the frame, creel pins for carrying bobbins for supplying roving to the rolls mounted 125 above the rolls in position so that the lead of the roving runs from the bobbins to the roving guides for the rolls, supported upon

low-friction bearings so that the resistance to rotation of the bobbins is so small as to be within the strength of the roving to overcome without stretching or breaking, and in 5 upwardly inclined position to permit observation of the bobbin thereon and access thereto for the removal of the empty bob-

bins and the putting on of full bobbins without interference with other bobbins, substantially as described.

ALBERT H. MORTON.
